TITLE FASTENING CLIP

Roger H. Stitt, Chicago, Ill., assignor to United States Gypsum Company, Chicago, Ill., a corporation of Illinois

Application November 26, 1930, Serial No. 498,292

17 Claims. (Cl. 72—20)

This invention relates to fastening devices, and has reference more particularly to fastening clips for securing acoustical or other types of tile to ceilings or walls of buildings.

5 In the erection of acoustical tiles, or other wall surfacing material, it is common to apply a cementing agent around the exterior back surface of the tile, this cementing agent being adapted to adhesively attach the tiles to the wall surface. 10 These acoustical tiles are often made of a base of mineral wool with a suitable binder, and are subject to expansion and contraction, so that a tile may loosen along one edge in spite of its adhesive attachment. It is therefore 15 desirable to have some form of mechanical attachment in addition to the adhesive so that the tiles cannot work loose from the wall surface.

An object of this invention, therefore, is to provide a mechanical attaching means for securing acoustical or other tiles to wall surfaces.

Another object of the invention is to provide a fastening means which may be utilized after a period of time following erection of the tiles to securely fasten any edge of the tile which 25 may have worked loose to the wall surface; also to improve fastening devices in other respects hereinafter specified and claimed.

Reference is to be had to the accompanying drawing forming a part of this specification, in 30 which

Fig. 1 is a plan view of a section of abutting tiles, with my improved fastening clip in place,

Fig. 2 is a sectional elevation through the tiles and ceiling surface, showing the mechanical fastening device,

Fig. 3 is a side elevation of the fastening device during erection, and

Fig. 4 is a perspective view of the improved fastening device.

40 The acoustical tiles 10, or any other kind of tiles, may be attached to a ceiling surface 11 by means of an adhesive substance 12, such as glue, asphalt, or adhesive having plaster of Paris as a base. The acoustical tiles may be made of mineral wool base with a binder and other ingredients, and are more or less subject to expansion and contraction due to changing atmospheric conditions, so that the adhesive 12 is sometimes broken loose from the wall surface.

45 The acoustical tiles are usually placed in series with edges in abutting relation, as shown in Fig. 2. They are often provided with beveled edges 13 so as to add to their architectural appearance.

The salient feature of my invention consists 55 in a metallic clip 14 of thin metal, which is

preferably coated with paint or baked enamel of a color matching that of the tile, to which it is applied. The clip 14 is preferably substantially rectangular in shape, except that one corner is formed into an annular collar or sleeve 60 15, having an internal diameter equal substantially to the external diameter of a nail 16, so that a tight fit between the two prevails. Thus, the nails 16 may be assembled with the clips before use without becoming displaced, and handling is thereby facilitated. The edge of the clip 14 adjacent the head 17 of the nail 16, is provided with a notched or severed portion 18, forming a pair of flanges 19 and 20, which extend outwardly from the body of the clip 14 at 65 70 an angle substantially equal to the bevel 13 of the tiles 10.

It will be observed that the sleeve 15 is so positioned that nail 16 is directed into the surface 11 at a slant. This feature is of particular 75 merit where the surface 11 is of plaster, as is commonly found in the interior of a building. Acoustical tiles are for the most part attached against such a surface, inasmuch as generally the need for acoustical treatment is not apparent 80 until all ordinary structural details of the interior are completed. A plastered surface is notoriously inadequate for retaining a driven nail, since the plaster disintegrates about the nail shank from the concussion incident to driving the nail, 85 and there is consequently no sufficient hold upon the nail to retain the same. However, since in the present construction the nails 16 are guided into and maintained in slanting relationship with the plastered surface by the clips 14, and since 90 the force tending to dislodge the nails is generally perpendicularly away from the surface, it will be readily apparent that a cantilever action will be developed by the nail shank in the plaster, whereby a sufficient grip is exerted upon the nail 95 to hold the same in place. The term "plaster" as herein used is intended to refer to any sort of cementitious wall facing over which the tiles may be erected.

In applying the clip, the said clip is pushed inwardly between the two tiles 10 until the flanges 19 and 20 substantially contact with the beveled edges 13 of the tile. Nail 16 is then driven inwardly a limited distance into the ceiling 11, and the driving is continued by the use of an ordinary nail set 21 until the nailhead 17 is concealed between the two tiles 10. In this finished position, only the flanges 19 and 20 will appear from the outside of the tiles as shown in Fig. 1, and since these flanges match in color with the tiles 110

themselves, they are not noticeable and yet serve effectively to attach the tiles to the ceiling surface 11.

I would state in conclusion that while the illustrated example constitutes a practical embodiment of my invention, I do not wish to limit myself precisely to these details, since manifestly, the same may be considerably varied without departing from the spirit of the invention as defined in the appended claims.

Having thus described my invention, I claim as new and desire to secure by Letters Patent.

1. In a fastener for tiles, a clip body of sheet metal, an annular collar formed on said sheet metal for receiving an attaching nail, and outstanding flanges on said fastener bent out of the plane of said clip body adapted to engage abutting tiles when said nail is driven into place, so as to fasten said tiles to a ceiling or wall surface.

2. In a building construction, a ceiling surface, a series of tiles adhesively attached in abutting relation to said ceiling surface, a sheet-like fastening clip interposed between abutting tiles, outstanding flanges formed on an edge of said clip and adapted to engage said tiles to prevent the disengagement of said tiles from said ceiling surface, and a nail engaging a portion formed on said clip independently of said outstanding flanges, said nail extending into said ceiling surface to attach said clip and said tiles to said ceiling surface.

3. In a device for fastening tiles in place, a clip body of sheet metal, a sleeve formed diagonally along one edge of said body for receiving an attaching nail, and outstanding flanges on said fastener adapted to engage abutting tiles when said nail is driven into place, so as to fasten said tiles to a ceiling or wall surface.

4. In a device for fastening tiles in place, a clip body of sheet metal, a sleeve formed diagonally along one edge of said body for receiving an attaching nail, and oppositely extending tile gripping flanges on another edge of said body adapted to engage abutting tiles when said nail is driven into place, so as to fasten said tiles to a ceiling or wall surface.

5. In a device for fastening tiles in place, a clip body of sheet metal, an annular collar formed on said body for receiving an attaching nail, and a plurality of flanges formed along one edge of the body by severing intermediate the ends, said flanges being bent in alternate opposite directions whereby to grip and fasten abutting tiles when said nail is driven in place.

6. In a device for fastening bevel edged tiles in place against a surface, a clip body of sheet metal, a plurality of flanges on one edge of said body bent to conform to the bevel edges of said tiles, and a nail engaging a portion of said clip and extending into said surface to attach said clip and said tiles to said surface.

7. In a building construction, a building surface covered by acoustical or similar tiles in edge abutting relationship, metallic clips securing the tiles against said surface, said clips comprising a substantially flat body portion interposed between the abutting edges of said tiles, means for securing said clips to said surface, and flanges on said body portion substantially contacting the edges of said tiles and being the only part of said clips apparent from the outside of said tiles when in place against said surface.

8. In a building construction, a pair of tiles against a building surface, said tiles being in edge abutting relationship, a sheet metal clip

interposed between said abutting edges and being nailed to said building surface, and a pair of oppositely disposed flanges on said clip, contacting with the outside of said abutting tile edges to retain said tiles in place, said flanges being coated with paint or baked enamel of a color substantially matching that of the tiles.

9. In a device adapted for resecuring tiles already more or less fastened in closely edge abutting relationship against a building surface, a clip body of sheet metal adapted to be interposed between said abutting edges without removing said tiles, means along one edge of said body for receiving a nail or the like for attaching said device to said building surface, and means along another edge of said clip body for engaging one or more tiles to retain the same in place against said building surface.

10. In a device for re-securing closely edge abutting tiles which are becoming loose from the surface to which they have been attached, a body of sheet material adapted to be interposed between the abutting edges of said tiles without removing said tiles, means for securing said body to said surface, and means along an edge of said body for engaging the edge of one or more tiles to re-secure the same against said surface.

11. In a building construction, a building surface, a pair of tiles facing said building surface, a fastening clip extending between abutting edges of said tiles and having attachment to said building surface by a nail engaging in a sleeve-like means formed on said clip, and a pair of flanges on said clip independent of said sleeve-like means, and contacting said tile edges to secure said tiles to said building surface.

12. In a fastener for tiles or the like, a clip body of sheet metal, a nail-engaging means formed by displacement of the metal of said body, outstanding flanges on said fastener bent out of the plane of said clip body and adapted to engage adjacent tiles, and a nail inserted in said nail engaging means in position to be driven into place in said surface.

13. In a clip for the purpose described, a clip body, means for engaging a tile, and means on said clip body for guiding and maintaining an attaching nail at a slanting angle relative to the plane of a surface into which said nail is to be driven.

14. A clip for the purpose described, comprising a clip body, a laterally extending flange on said clip body for engagement of a tile, and means in said clip for guiding and maintaining a nail diagonally with relation to said flange, so that said nail may be driven into a surface at a slanting angle.

15. In a building construction, a plastered building surface, a tile attached to said surface, a metallic clip for retaining said tile against said surface, said clip having a body portion, means on said body portion for engagement of said tile, and means in said clip for receiving a nail, said last mentioned means being formed to guide and maintain said nail at a slanting angle relative to said plastered surface.

16. In a clip for the purpose described and in combination, means for engaging a tile, a nail, and means independent of said engaging means for receiving said nail in ready-to-drive position to direct said nail into a surface, said last mentioned means being in substantially tight engagement with said nail, whereby to retain said nail in assembled relation with said clip before attaching said clip to said surface.

17. In a clip for the purpose described and in combination, a substantially flat, metallic clip body, a flange extending at an angle to said clip body and adapted for engagement with a tile, an attaching nail, and means for receiving said nail to guide the same at a predetermined angle into a surface into which said nail is to be driven, said nail being in removable but firm engagement with said receiving means and extending partially therethrough in position to be driven into said surface.
